SUPPORTING STAND

Otto J. Gerschefski, Meriden, Conn., assignor to
The Herco Art Manufacturing Company, Meri-
den, Conn., a corporation of Connecticut

Application April 3, 1934, Serial No. 718,816

6 Claims. (Cl. 248—165)

The present invention relates to sectional supporting stands, sectional lighting fixtures and the like.

The present invention contemplates a system of fittings whereby supporting stands for lamps or articles of furniture or sectional lighting fixtures may be made up out of a standard central body member and a plurality of radiating arms or legs, the central supporting member and the 5 arms or legs being so designed that the central body member can cooperate with a selected set of radiating arms or legs. These radiating members are provided with lugs of standard size and dimension varied only in accordance with the 10 number of such radiating members as will comprise a set and so arranged that the lugs may be received in the body member and secured to it so that the radiating members are exactly located in position and firmly held in such position. 15

According to the present invention, these radiating members are preferably in the form of castings made in permanent molds and each casting, irrespective of its ornamental design is provided with a lug. The lugs on all the castings 20 forming the series of fittings are identical with one another except for the angular width of the lug. These widths are so chosen that 2, 3, 4, 5, or 6 lugs of identical size will complete a circumference and fit the body member so as to properly space the radiating members and when clamped in place, secure them in fixed position.

The present invention also contemplates that the radiating arms or legs shall each be provided with a surface adapted to engage the outer surface 25 of the body member so as to further reinforce the structure and prevent loosening of the parts once they have been properly secured together.

In carrying out the present invention, the castings are preferably made in molding apparatus such as is shown in my application for molding apparatus and method of making the same, executed and filed concurrently herewith and bearing Serial No. 718,817. This casting process contemplates the making of the lugs and adjacent parts of the casting uniform irrespective of the ornamental design of the casting and varied only in accordance with the number of such radiating members as shall form a set.

The accompanying drawings show, for purposes of illustrating the present invention, several of the many embodiments in which the invention may take form, it being understood that the drawings are illustrative of the invention rather than limiting the same. In these drawings:

Fig. 1 is a longitudinal sectional view through an assemblage having four arms or legs.

Fig. 2 is a transverse sectional view on the line 2—2 of Fig. 1.

Figs. 3a, 3b, 3c are fragmentary sectional views

taken on the line 3—3 of Fig. 1 illustrating three arm, four arm, and six arm assemblages, respectively.

Fig. 4 is a fragmentary side elevational view showing the lug for a four arm assemblage.

Figs. 5 and 6 are fragmentary elevational views taking the direction of arrows 5 and 6 of Fig. 4, parts being in section.

Fig. 7 is a diagrammatic elevational view illustrating a fixture body or the like made up of two sets of arms and assemblages.

Fig. 8 is a perspective view of a lamp or furniture base or stand employing four legs.

Fig. 9 is a similar view of a three leg structure provided with a ring.

Fig. 9a is a fragmentary sectional view showing a detail of Fig. 9.

Fig. 10 is a perspective view illustrating a body part of a five arm lighting fixture.

As shown in Figs. 1 and 2, the assemblage employs a central body member 10, a plurality of radiating members 11 which may be in the form of arms or legs of any desired ornamental shape, a threaded rod or tube 12, and a nut 13, with or without washers 14.

The body member 10 is here shown as having a threaded hole 15, an outer surface 16 which is preferably cylindrical (although it may be slightly tapered) and an inner conically tapered surface 17. The bore of the body member 10 is 20 preferably turned to have a slightly larger diameter as indicated at 18 to provide clearance.

The radiating members 11 are each provided with laterally extending portions 20 and each of these laterally extending portions is provided with 35 a lug 21 extending parallel to the adjacent part of the casing 11.

There may be three of these lugs 21 as indicated in Fig. 3b, or four of them as indicated in Figs. 2, 3a, and 4 to 6, or six of them as indicated in Fig. 40 3c. Sectional structures employing two, five, or more than six radiating members are not indicated in these drawings, although they may be made up if desired. The outer surface 22 of these lugs is conical and of the same taper as the 45 tapered bore in the housing so that these conical surfaces closely fit. The angular extent of the lugs is determined by the number of arms to be employed in the set. In a four arm or leg structure, the angular width of each lug is 90° as will be apparent in Figs. 2, 3a, 5 and 6. In the three arm device, the angular extent of each lug is 120°, as indicated in Fig. 3b, and in the six arm device, the angular extent of each is 60°, as indicated in Fig. 3c.

The side faces of the lugs are indicated by the short radial lines 23 appearing in the drawings. Each of the lugs is hollowed out as indicated at 24 to accommodate the tube or rod 12 and to facilitate assembly. The smaller 55 60

end of each lug is preferably bevelled or chamfered as indicated at 25.

The lateral extensions 20 of these castings or arms 11 which carry the lugs are made of 5 standard width, as will appear from Figs. 3a, 3b, and 3c and each occupies not over 60° so that when this standard sized extension is employed on the six arm assemblage, there is nothing to interfere with bringing the parts to the desired 10 position. Should assemblages with more than six radiating arms be contemplated, the extensions and legs would be designed accordingly.

When the parts are assembled, the tightening up of the nut on the rod or tube 12 acts to press 15 the lugs into the tapered bore and brings all the parts into an exceedingly close, tight and compact assemblage in which looseness is completely avoided. This is on account of the accurate manner in which the parts are made.

20 Fig. 7 illustrates a structure having two body members 30 and 31, an upper set of arms 32 and a lower set of arms 33 and the outer ends of these arms may be secured together, as at 35, in any desired manner either directly or by means of a 25 ring. The inner ends of the arms have lugs 32' and 33' similar to the lugs 21. The two bodies 30 and 31 are carried on a rod or tube 34, the whole assemblage being secured together by a nut indicated at 34'.

30 The design of the arm or leg may be varied widely and also the use to which these assemblages may be put. Fig. 8 is an assemblage having four arms 40 carried on an ornamented central body member 41 and having their outer ends 35 free. This would form, for example, a four legged lamp support, the wiring being carried up through the tube 12. In Fig. 9 a construction similar to Fig. 8 is shown, except that there are three arms each of which carries a threaded stud 40 42 which extends through a ring 43 and is secured in place by a nut 44. Fig. 10 shows an arrangement for a lighting fixture having five arms 45, for instance, one of which is not indicated. These arms are carried on a body member indicated at 46. In the constructions of Figs. 45 8, 9, and 10 ornamental nuts are indicated at 47 instead of the nut shown at 13 in Fig. 2.

It is obvious that the invention may be embodied in many forms and constructions, and I 50 wish it to be understood that the particular forms shown are but a few of the many forms. It is also obvious that various modifications and changes are possible and, therefore, I do not limit myself in any way with respect thereto.

55 What is claimed is:

1. In combination, a body member having a conically tapered bore, a plurality of radiating members each provided with an angular extension opposed to the open end of the body, a lug 60 projecting from one side of said extension and disposed in said bore, each lug being too short to reach the bottom of the bore and having a conical face to fit the tapered wall of the bore and side faces in dihedral planes to engage corresponding side faces of adjacent lugs, and means 65 to exert axial pressure on said extensions and the body member in a direction to press the lugs into wedging engagement with the wall of said bore.

2. In combination, a body member having a 70 conically tapered bore, a plurality of radiating members each provided with an angular extension opposed to the open end of the body member, a lug at one side of the free end of said extension and disposed in said bore, each lug being 75 too short to reach the bottom of the bore and

having a conical face to fit the tapered wall of the bore and side faces in dihedral planes to engage corresponding side faces of adjacent lugs, a rod extending axially through the body member in threaded connection therewith and between the lugs, and cooperative threaded means for exerting axial pressure on the extensions and body member in a direction to press the lugs into wedging engagement with the wall of said bore. 10

3. In combination, a body member having a conically tapered bore, an axial rod onto which the body member is threaded, a plurality of radiating members each provided with an angular extension opposed to the open end of the body member, a lug at one side of said extension and disposed in said bore, each lug being too short to reach the bottom of the bore and having a conical face to fit the tapered wall of the bore, side faces in dihedral planes to engage corresponding side 20 faces of adjacent lugs and an inner face spaced from the rod, and a nut threaded on said rod and bearing on the extensions to force said lugs into wedging engagement with the wall of said bore when tightened. 25

4. In combination, a body member of circular outer cross section and having a conically tapered bore, an axial rod on which the body member is threaded, a plurality of radiating members each provided with an angular extension opposed 30 to the open end of said bore, a lug offset from one side of said extension and disposed in the bore, each lug being too short to reach the bottom of the bore and having a conical face to fit the tapered wall of the bore and side faces in 35 dihedral planes to engage corresponding side faces of adjacent lugs and an inner face spaced from the rod, each radiating member having a portion with a concave surface opposite the conical surface of its companion lug to fit the convex 40 outside surface of the body member, and a nut threaded on the rod and bearing on opposed sides of said extensions to force the lugs into wedging engagement with the wall of said bore and the opposed concave and convex surfaces of said radiating members and the body member. 45

5. In a device of the class described, a substantially annular support, a leg or arm comprising 50 a casting having a body part, an angular extension, and a lug carried at one side of said extension in spaced relation to an adjacent portion of the body part, the lug having an outer surface of conical tapered shape and side surfaces in radial dihedral planes with respect to the axis of a cone, the inner surface of said portion of the 55 body part being a co-axial surface whereby the opposed surfaces of the portion of the body part and its companion lug wedgingly engage opposite faces of said support.

6. In combination, a cylindrical body member 60 having a conically tapered bore, a plurality of radial members each provided with an offset and substantially parallel lug disposed in the bore, each lug being too short to reach the bottom of the bore and having a conical face to fit the tapered wall of the bore and side faces opposed to corresponding side faces of adjacent lugs, each radial member having a portion with a concave surface opposite the conical surface of its companion lug to fit the outside surface of 65 the body member, and means to exert axial pressure on the radial members and the body member to force the lugs into wedging engagement with the wall of said bore. 70

OTTO J. GERSCHEFSKI. 75
